UNITED STATES PATENT OFFICE

CHARLES C. JESSEN, OF PASSAIC, NEW JERSEY, ASSIGNOR TO NAPON RAYON CORPORATION, OF CLIFTON, NEW JERSEY, A CORPORATION OF DELAWARE

APPARATUS FOR TREATING ARTICLES WITH LIQUID

Application filed July 28, 1927. Serial No. 209,020.

At a certain stage in the manufacture of rayon or artificial silk it is necessary to wash the filament, wound up in packages, as on spools, with water to remove therefrom chemical substance existing thereon. The washing should be thoroughly accomplished, and this is found to be most effectively done if effected so that the liquid falls on the packages and then drops from them, as by their being supported above or clear of any accumulation of the liquid in which the washed-off chemical would remain. But it is also found that the liquid should not impinge against the packages with any appreciable force, since otherwise the windings of the filament, which are usually at this stage formed quite loosely, are likely to be disturbed so that in the unwinding of the packages snarling of the filament with consequent wastage thereof and loss of time are a result. Hence it is found that spraying the liquid directly against the packages is not desirable, since the jets are likely to disarrange the windings and by a jet-delivery of the liquid some parts of the packages do not receive their share of the wetting.

What I aim to accomplish by this invention is to provide an apparatus by which the filament packages will be thoroughly and uniformly wetted by the washing liquid, each throughout the whole extent of its wound mass, and that in such a way that the application of the liquid shall be gentle and so not calculated to disturb the windings of the packages. This I have accomplished principally by resorting to means which in effect produces a precipitation of the washing liquid after the manner of rain, the liquid falling on the packages in drops varying in size and profusely scattered. But in connection with such means I preferably use a novel form of means for conveying the packages while they are being thus treated with the washing liquid, whereby every portion of the circumferential surface of each package will be certain to receive the falling liquid directly and the thorough and uniform soaking of the packages will be insured.

While I shall herein explain the invention with reference to the treatment of wound

filament packages it will be understood that it is also applicable in certain aspects thereof to other articles and materials. It will be also understood that other liquids than washing liquids are adapted to be applied in the use of the invention.

The accompanying drawing fully illustrates the invention in a case where wound rayon packages are to be washed,

Fig. 1 being a fragmentary side elevation, partly broken away, showing the essential parts of an apparatus embodying the invention;

Fig. 2 a sectional view on line 2—2, Fig. 1;

Fig. 3 a fragmentary plan of the liquid distributing sheet or wall;

Fig. 4 a sectional view thereof taken lengthwise of one of the rows of tongues therein; and

Fig. 5 illustrates a detail.

1 designates the frame of the apparatus, which is built usually of considerable length relatively to its width and height. Extending lengthwise of and parallel to one side of the frame is a main pipe or header 2 for the washing liquid or other liquid of treatment, the same having at suitable intervals and extending crosswise of and between the sides of the frame smaller delivery pipes 3 equipped with spray-heads 4 which preferably deliver at the general inclination shown in Fig. 1.

At each end of the machine there is journaled in the opposite sides thereof a shaft 5 having sprocket wheels 6. Revoluble in the supporting means afforded by the frame and these sprocket wheels and around the sprocket-wheels extend two endless chains 7. These chains, with certain other parts to be described, form a rotary conveyor for the packages or other bodies to be treated whose rotary movement is around a horizontal axis; and for imparting motion thereto either of the shafts may be constantly rotated from any suitable means (not shown). The conveyor includes carriers (which may also form links of its constituent chains) arranged at suitable intervals circumferentially thereof. Each carrier, 8, has a bifurcated projecting portion 8^a which is wider than the chain proper. On account of the considerable

length of the upper and lower stretches of each chain it is desirable to support such stretches between the corresponding sprocket wheels 6. Hence on the floor 9, under each 5 chain-stretch, is a track or rail 10 (here of inverted channel-iron) on which the carriers of such lower stretch slide. Suitably supported in the frame above each of these rails is another such rail 11 of channel-iron, but 10 with its channel side up, and on the sides or flanges of this rail the carriers of the upper stretch of such chain slide.

For each carrier of one chain there is a complementary or directly opposite carrier 15 on the other. The packages, arranged on suitable rods as supports, are to be placed on the conveyor at one end of the apparatus by one attendant and upon being conveyed thereby to the other end, meanwhile undergoing treatment, are to be removed by another attendant. For facilitating the feeding of the packages to and removal thereof from the machine and for insuring thoroughness and uniformity of the treatment the 20 following parts are employed: Each of the mentioned rods, 13, is formed with one end square, as at 13^a, Fig. 5, and the other round, as at 13^b. The packages consist of suitable cylindrical cores 15 (one appearing empty 25 in Fig. 2) with the filament 16 cross wound thereon (Fig. 2), their cores being of greater diameter than that of the rods. When the packages are formed a number of them are slipped over a rod which is thereafter kept 30 generally horizontal until the packages are to be removed therefrom. Each rod, loaded thus with the packages, is mounted in a portable crate or rack, which then affords a supply from which the attendant who is feeding 35 the machine of this invention obtains them for that purpose. The mentioned carriers on one chain have fixed (non-rotary) horizontal transverse spindles 17 each formed with an outwardly open or U-shaped bearing 40 socket 17^a at its inner end. In the complementary carriers on the other chain are journaled horizontal transverse rotary spindles 18 each equipped at its inner end with a square socket 18^a and at its outer end having a 45 sprocket-wheel 18^b fixed thereon. Each 50 spindle 18 and its sprocket wheel and socket form a rotator for a rod and the packages carried thereby. These sprocket-wheels mesh 55 with a rack 19, which is here in the form of a chain fixed at both ends to the frame 1 and extending horizontally and lengthwise of said frame. The attendant who is feeding 60 the machine takes the loaded rods from the mentioned rack one after another and having fitted the squared end thereof in socket 65 18^a places the other or round end in socket 17^a. Thereupon, as it is carried along by the conveyor each rod is rotated by the engagement of the corresponding sprocket-

wheel 18^b with the rack 19, resulting in rotation of the packages strung on the rod.

A tunnel-like structure or housing 20 is suitably supported in the frame 1, as by being hung from the top cross-beams 1^a thereof, 70 having top, bottom and side walls, and it may be also end walls, as shown. This houses the mentioned spray-heads 4, being designed to confine the resulting mist within its space the extent of which lengthwise and transversely is approximately that of the conveyor. The bottom wall 21 has a special construction designed to cause liquid falling thereon as a spray or in drops to fall therefrom substantially like rain in accordance 75 with my invention. That is to say, such wall has openings 21^a and under each opening a tongue 22 which is preferably inclined downwardly and also tapers toward its lower or free end. The openings and tongues may be formed by providing bent (preferably V-shaped) slits in the material of the wall (which is preferably sheet material) and then bending downward the tongues resulting (Figs. 3 and 4). They may be formed 80 in the proper size and such proximity to each other (as in rows in which the tongues of one row are staggered with references to those of the next and project between the latter—Fig. 3) as the profuseness of the "rain" 85 which they are to produce may require. When the machine is in operation with such distributing means as I have just described interposed between the packages or wound bodies being treated and superjacent spraying or equivalent means (as 4) for delivering the liquid in drops generally over the area represented by so much of said bodies as are at the time positioned for treatment 90 the liquid falling on the distributor trickles down and falls of its own weight on said bodies, after the manner of rain, the tongues, it being noted, intercepting all liquid that might otherwise fall through the openings 95 in the form of jets, or subject to the impelling force of the spraying. Said bodies in this operation become thoroughly and uniformly drenched, in part because the "rain" 100 effect is profuse and scattered over the whole area represented by the packages being conveyed and in part because each package is made to rotate a number of times as it passes from one to the other end of the machine, so that all parts of its circumference are subjected to the falling liquid. The inclinations of 105 the sprays and of the tongues are relatively such that with respect to any spray (or jet thereof) the tongues practically completely shield the packages from such sprays (or jets thereof) so that none of the latter which 110 may pass through the openings can as such reach the packages. A misty, foggy or moisture-laden condition of the atmosphere of course exists above the wall 21, but this is 115 confined by the tunnel, which, though it may 120

be open at one end for inspection, is preferably closed at the other to prevent the water-laden air in the tunnel being impelled therefrom by the draft it is found is otherwise set up by the inclined sprays; the closed end in such case would be the left-hand end in Fig. 1.

The liquid which falls on the packages drips therefrom into a receptacle 23 suitably supported by frame 1 below the packages being conveyed, from which it may be discharged by a pipe 24 into a sewer 25 or other receiver.

I believe that it is new in machines of this class to provide a conveyor revoluble in the supporting means around a substantially horizontal axis and having substantially horizontal bearings for the articles extending transversely of the path of travel, and arranged at intervals circumferentially, of the conveyor and also having revoluble rotators for the articles axially alined with said bearings, and means to rotate the rotators in the conveyor while moving with the latter.

It is new, I believe, to treat with a liquid a body of absorbent material having an approximately cylindrical bore by hanging it on a rotary support of less diameter than said bore and so that the support penetrates the bore and has its axis of rotation substantially horizontal, and then passing the support and said body while rotating the support on said axis, and thereby also frictionally rotating said body, through liquid falling substantially as a shower.

Further, it is new, given means to support the material to be wetted with liquid, to provide liquid distributing means including a wall arranged in a substantially horizontal plane over the space occupied by said material and having numerous openings therethrough arranged over said space and obstructing devices respectively underlying said openings and having upper surfaces inclined generally downward, and means to shower liquid upon said wall, said devices being preferably tapered toward their lower ends. It is not indispensable in the broad aspect of the invention that the specific example, as herein shown and described, be adhered to, viz, that said obstructing devices be tongues formed by bending down the portion of a piece of sheet material (constituting said wall) within the bend of a bent slit formed in the sheet material.

It is further new to provide means to deliver a liquid shower, as by sprays forcibly or otherwise delivering, a chamber to house the shower closed at the top and opposite sides, a bottom for the chamber obstructing the fall of the shower and having numerous openings throughout a given area and through which the liquid may then pass downward in divided state, and means to convey the articles to be wetted under the

chamber and through the liquid falling from said bottom in such divided state. Spraying the liquid directly on to the packages is not only likely to disturb their windings, as hereinbefore pointed out, but to cause a wetting of the machine and the vicinity of the machine and create a mist or liquid-laden atmosphere around the machine which is very undesirable. In my machine any spattering and consequent misty and liquid-laden atmosphere are confined within a chamber (the tunnel), from which the liquid falls gently on the packages and so as to drench the same thoroughly, and the machine itself and all about it are kept in dry condition.

Having thus fully described my invention, what I claim is:

1. The method of treating with a liquid a wound filamentous body having an approximately cylindrical bore which consists in hanging the body on a rotary support of less diameter than said bore and so that the support penetrates the bore; such support having its axis of rotation substantially horizontal, and then passing the support and said body while rotating the support on its said axis, and thereby also frictionally rotating said body, through liquid falling substantially as a shower.

2. In combination, means to support the material to be wetted with liquid, liquid distributing means including a wall arranged in a substantially horizontal plane over the space occupied by said material and having numerous openings therethrough arranged over said space and obstructing devices respectively underlying said openings and having upper surfaces inclined generally downward, and means to shower liquid upon said wall.

3. In combination, means to support the material to be wetted with liquid, liquid distributing means including a wall arranged in a substantially horizontal plane over the space occupied by said material and having numerous openings therethrough arranged over said space and obstructing devices respectively underlying said openings and having upper surfaces inclined generally downward and each being tapered toward its lower end, and means to shower liquid upon said wall.

4. In combination, means to support the material to be wetted with liquid, a liquid distributing wall of sheet material arranged in a substantially horizontal plane over the space occupied by said material and having numerous bent slits formed therein over said space and the portion thereof within the bend of each such slit bent downward at a general incline, thereby leaving openings in the wall and depending inclined tongues respectively under the openings, and means to shower liquid upon said wall.

5. In combination, means to deliver a liq-

uid shower, a chamber to house the shower closed at the top and and opposite sides, a bottom for the chamber obstructing the fall of the shower and having numerous openings throughout a given area and through which the liquid may then pass downward in a divided state, and means to convey the articles to be wetted under the chamber and through the liquid falling from said bottom in such divided state.

10 In testimony whereof I affix my signature.
CHARLES C. JESSEN.
